UNITED STATES PATENT OFFICE.

PERCY WADE, OF WASHINGTON, DISTRICT OF COLUMBIA, ASSIGNOR TO THE WELDIT COMPANY, A PARTNERSHIP COMPOSED OF PERCY WADE AND CARL L. CAMERON, OF WASHINGTON, DISTRICT OF COLUMBIA.

OIL-BURNER SYSTEM AND TORCH THEREFOR.

1,353,683.

Specification of Letters Patent. Patented Sept. 21, 1920.

Application filed October 20, 1919. Serial No. 331,768.

To all whom it may concern:

Be it known that I, PERCY WADE, a citizen of the United States, residing at Washington, District of Columbia, have invented 5 certain new and useful Improvements in Oil-Burner Systems and Torches Therefor; and I do hereby declare the following to be a full, clear, and exact description of the invention, such as will enable others skilled 10 in the art to which it appertains to make and use the same.

This invention relates to oil burner systems and torches therefor.

An object of this invention is to provide 15 an improved system for oil burning torches for preheating metal for welding purposes and to provide improved torches therefor.

A further object of this invention is to 20 provide an improved system for producing pressure for oil burning torches and to provide a system whereby pressure is produced by the water system of the city or locality wherein the shop is located, and to provide auxiliary means for utilizing air pressure 25 when such water system is disabled and thereby eliminate the necessity of constantly carrying a means for generating air pressure.

A further object of this invention is to 30 provide an improved means for mounting torches throughout the shop and to provide torches which may be held in any predetermined position automatically and without manually manipulating them.

35 A further object of this invention is to provide an improved means for distributing a plurality of torches throughout a shop.

A further object of this invention is to 40 provide an improved system of heating and preheating metals for welding purposes.

A further object of this invention is to 45 provide a safety system for oxyacetylene welding and combine such a system with the means for generating pressure in an oil burning preheating torch.

A further object of this invention is to 50 provide a torch that can be easily cleaned, one of simple and durable structure and one that can be taken out into stormy weather, and to provide a means for protecting a retort during stormy weather that is easily gotten out of the way when not so desired.

A further object of this invention is to 55 provide a torch having a retort which when

carbonized can be easily cleaned and to avoid the common trouble of popping of 60 torches when they get too hot which causes them to cease working, and further to provide for an easy means of removing the carbonized residue from a retort of torch of this character.

A further object of this invention is to 65 simplify and improve the construction of an oil burner.

With these and other objects in view the 70 invention consists of the construction, the combination and in detail of arrangement as hereinafter more fully described and claimed.

In the drawings:

Figure 1 is a diagrammatic view of my 75 system.

Fig. 2 is a medial longitudinal section partly in elevation of my torch.

Fig. 3 is a plan view.

Fig. 4 is a section at 4—4 of Fig. 3.

In detail the invention comprises a plurality of torches 2 pivotally mounted at 3 on rod 4, said rod 4 telescoping into a pipe 5 and held by a lock nut at 6. Said pipe 5 is mounted on a transverse pipe 6, pipe 6 being anchored to wall 7. Torches 2 are fed by rubber hoses 8 from a pipe 9 through a pressure gage 10 controlled by a valve 11, pipe 9 leading from a tank 12. Tank 12 contains both kerosene, or other oil, and water, water being supplied through a conduit 13 and oil being supplied through a perforation 14, the said water being from the usual city water supply and being under the ordinary city pressure. The water pressure is supplied through a conduit 15 which is connected to the city water supply and connected to the conduit 13. The supply of water for the tank 12 is regulated by means of a valve 16. A glass gage 17 is mounted on the end of tank 12 to indicate the relative levels of water and oil in said tank.

It is obvious that liquids of lesser specific gravity than water when mixed that these liquids will remain in the upper portions of the tank as illustrated in the drawing in the tank 12 and that water entering said tank through conduit 13 from a city water system under pressure of say forty lbs. per square inch will force the said lighter liquid, which in this case is usually kerosene, out through conduit 9 to the burn-

ers 2 under substantially the same pressure as the city water system. It is obvious further that in filling tank 12 by the opening of perforations 14 and the opening at the 5 same time of a cock 18 that very little attention need be given to the filling of this tank and that it will be unnecessary to disturb the pressure or open any valves in relation to the pressure system inasmuch as 10 the water as supplied by the pressure system will run out through the opening provided by cock 18 and continue to do so while the tank is being filled and that all that is necessary to observe is when the oil begins to 15 run from the spigot having cock 18, when it will be known that the tank 12 is full.

In detail the burner includes a retort comprising a piece of tubing 19 having ends 20 plugged at 20 and 20'. The plug 20' is perforated at 21 and 22, receiving through perforation 21 a pipe 23 and through perforation 22 a pipe 24. Pipe 23 has affixed in its end a washer 25, the purpose of washer 25 being to prevent liquid from running back 25 in pipe 23 when the torch is in an angular position relative to the earth's surface. Oil is admitted into retort 19 through pipe 23, is there heated into a vapor by the usual action of the flame beneath a retort of this 30 character, the said flame in this case being through a tubular chamber 26 and the said tubular chamber 26 being perforated at its top at 27 with preferably four circular holes disposed and of approximately the relative 35 diameter as illustrated. The vapors generated in said retort pass out through conduit 24 and down and backward through the nozzle 28 into said chamber 26 and are mixed with air in the usual manner. Conduit 24 40 is tubular and longitudinal relative to retort 19 and provided with a plug 29 so that in case of carbonization or otherwise fouling plug 29 can be removed and conduit 24 quickly and easily cleaned. The structure of 45 retort 19 and its relation to conduit 24 is such that it is obvious that any carbonization can be quickly and easily cleaned out. Retort 19 is so mounted relative to chamber 26 that it can be instantaneously detached 50 therefrom and the whole burner quickly cleaned. The mounting is as follows: Made integral with chamber 26 is a rectangular casing 30 perforated at 31 and 31' to receive the bifurcated ends 32 and 32' affixed 55 to retort 19. Thus by the longitudinal move-

ment of retort 19 the bifurcated end 32 can be pulled from the perforations 31 and 31' and the latter disassembled and removed from the chamber 26. The retort is held in relative affixed relation to said chamber by 60 a bearing 33 for a cover 34. The cover 34 is a storm protection pivoted at 33 so that by angular movement upon its pivot exposure can be regulated as desired. Retort 19 is further positioned and held relative to 65 chamber 26 by strips 35. Affixed to chamber 26 is bar 4 perforated at 36 so as to form the pivot 3, and locked by a set screw 37 to a stud affixed to the side of said chamber 26. 70

What I claim is:

1. In combination, a cylindrical combustion chamber made unitary with a retort casing in the top of said combustion chamber, and a retort mounted in said casing, and 75 slides mounted in said retort to enter perforations in said casing.

2. In combination, a cylindrical combustion chamber, a relatively smaller cylindrical retort, said retort superposed of said combustion chamber and mounted in a rectangular casing made unitary with said combustion chamber, and the said mount comprising perforations in said casing and bifurcated ends upon said retort slidable in said 85 perforations, and means for locking said slides in predetermined relation.

3. In an oil burner, in combination, a retort, a cover for said retort, means for mounting said retort by slides, and means 90 for locking said slides, said locking means forming a pivot for said cover.

4. In combination, a cylindrical combustion chamber made unitary with the retort casing on the top of said combustion chamber, a retort mounted in said casing and 95 means for mounting said retort in the casing.

5. In combination, a cylindrical combustion chamber, a retort superposed of said 100 combustion chamber and mounted in a rectangular casing, made unitary with the combustion chamber, the said mounting comprising perforations in said casing and bifurcated ends upon said retort slidable 105 in said perforations and means for locking said slides in predetermined relation.

In testimony whereof I affix my signature.

PERCY WADE.
